Primary Examiner — Michelle E. Wilson*Assistant Examiner* — Caitlin A Laverty(74) *Attorney, Agent, or Firm* — Merchant & Gould P.C.(57) **CLAIM**

The ornamental design for a pill organizer as shown and described.

DESCRIPTION

FIG. 1 is a top perspective view of a pill organizer, according to the new design;

FIG. 2 is a bottom perspective view of FIG. 1;

FIG. 3 is a front view of FIG. 1;

FIG. 4 is a back view of FIG. 1;

FIG. 5 is a right side view of FIG. 1;

FIG. 6 is a left side view of FIG. 1;

FIG. 7 is a top plan view of FIG. 1; and,

FIG. 8 is a bottom plan view of FIG. 1.

The broken lines show portions of the pill organizer that form no part of the claimed design.

1 Claim, 8 Drawing Sheets(56)
